ABSTRACT OF THE DISCLOSURE

A burner and feedstock injection assembly for a carbon black reactor having three concentric pipes:
a center pipe for feedstock;
a second pipe, surrounding the center pipe;
a third pipe, surrounding the second pipe;
and a plurality (preferably three) of fuel-oil pipes disposed within the annulus between the second and third pipes;
the ends of each of these fuel-oil pipes being equipped with a spray nozzle inclined at an angle with respect to the axis of the center pipe. These fuel-oil pipes are for the introduction of combustion fuel into the reactor. Preferably, the assembly also includes a substantially cone-shaped flameholder device mounted concentrically about the third pipe at the end thereof, such cone flaring outwardly toward the interior of the reactor, such cone being comprised of a plurality of vanes or louvers each of which is twisted at the outer ends thereof.

BACKGROUND OF THE INVENTION

Field of the invention

This invention relates to the production of carbon black by the injection of a suitable hydrocarbon feedstock into an elongate reactor or combustion chamber containing high-temperature flames and gases, and more particularly to a burner and feedstock injection assembly for burning a normally liquid hydrocarbon as fuel to provide the heat necessary for the pyrolysis of the feedstock to form carbon black. Such assembly also includes means for supplying the feedstock to the reactor.

In many instances gas is used as a fuel to the burner; however, in situations where gas is not available, or is not available at an economical price, it is desirable to have a burner which is designed for the use of a normally liquid hydrocarbon fuel. The main object of this invention is to provide a burner which will operate satisfactorily on a normally liquid fuel rather than gas.

Description of the prior art

Applicants do not claim that oil (rather than gas) burners for carbon black reactors are novel per se. The following patents disclose specific fuel-oil burner injection systems designed for specific carbon black reactors: 3,003,854; 3,060,003; 3,290,120; and 3,501,274. U.S. Pat. No. 3,443,761 discloses certain of the features of the present invention; however, it can readily be seen that the assembly of that patent is different and is suitable only for use with a gaseous fuel.

SUMMARY OF THE INVENTION

This invention is a burner and feedstock injection assembly for an elongate substantially tubular carbon black reactor comprising:

a center pipe for introduction of feedstock into the reactor, one end of said pipe terminating within the reactor and being equipped with a spray nozzle;
a second pipe, concentrically disposed about the center

2

pipe, one end of the second pipe terminating approximately flush with the end of the center pipe within the reactor;
a third pipe, concentrically disposed about the second pipe, one end of the third pipe terminating within the reactor at a point upstream of the end of the center pipe;
a plurality of fuel-oil pipes disposed within the annulus between the second and third pipes and axially parallel to said pipes, said fuel-oil pipes terminating at a point within the reactor downstream of the end of the third pipe but upstream of the end of the center pipe, the ends of said fuel-oil pipes being connected with a plurality of spray nozzles each of which is inclined at an angle of about 15°—45° from the axis of the center pipe;
means for supplying carbon black feedstock to the center pipe;
means for supplying cooling medium to the annulus between the first and second pipes;
means for supplying a normally liquid hydrocarbon fuel to the fuel-oil pipes;
means for introducing a stream of process air into said reactor; and
means for directing said stream of process air downstream along the outside of the third pipe.
Preferably, the assembly also includes a flameholder or air distribution device comprising a substantially cone-shaped device mounted concentrically about the third pipe at the end of said third pipe, said cone flaring outwardly toward the interior of the reactor at an angle of about 5°—30° (preferably 10°—25°) from the vertical, said device being comprised of a plurality of vanes or louvers each twisted at the outer end thereof to an angle of about 10°—25°.
Desirably, the assembly also includes means for supplying air to the annulus between the second and third pipes, together with an annular passageway between the outer circumference of the second pipe and the nozzle ends of the fuel-oil pipes connecting such annulus with the interior portion of the reactor.

BRIEF DESCRIPTION OF THE DRAWING

45 FIG. 1 is an elevational view partly in section illustrating the preferred embodiment of the burner and feedstock injection assembly;
FIG. 2 is a view taken along the line 2—2 of FIG. 1;
FIG. 3 is a longitudinal view, partly in section, of one 50 form of a suitable carbon black reactor including the preferred burner and feedstock injection assembly;
FIG. 4 is a longitudinal view, partly in section, showing another suitable form of carbon black reactor including the preferred burner and feedstock injection assembly.

DESCRIPTION OF THE PREFERRED EMBODIMENTS

Referring to FIG. 1, burner and feedstock injection assembly 1 will first be described. The feedstock line is center pipe 2 which is slideably mounted within axial pipe 3 and sealed therefrom by means of suitable packing glands included within closure member 4. Center pipe 2 is provided with guides (as shown) for proper positioning within axial pipe 3. The downstream end of center pipe 2 is provided with a suitable spray nozzle 5, which can be any conventional commercially available nozzle, preferably of the hollow cone type.

The upstream end of axial pipe 3 is provided with a T-connection 6 for introduction of air into the annulus between the center pipe and the axial pipe.

The tip of nozzle 5 terminates in approximate flush relationship with axial pipe 3.

Axial pipe 3 is slideably mounted within the assembly 1 by means of closure member 7 equipped with packing glands as shown.

As suggested above, the flow of air through axial pipe 3 serves to keep the nozzle 5 from becoming overheated. It is within the scope of this invention to surround pipe 3 with a water-cooled jacket so that the burner assembly can be cooled with water rather than air. A specific water-cooled jacket assembly is disclosed in U.S. patent application Ser. No. 59,962 filed July 31, 1970 and now abandoned in favor of continuation-in-part application Ser. No. 184,934 filed Sept. 29, 1971.

Tubular member or pipe 8, which is mounted concentrically about the axial pipe 3, is preferably equipped near the upstream end with expansion joint 9, which in turn is secured to annular chamber 10. Annular chamber 10 in turn is equipped with pipe 11 for introduction of fuel oil in a manner to be described below.

Communicating with chamber 10 are a plurality (preferably three) of fuel-oil pipes 12, one of which is shown in FIG. 1. These fuel-oil pipes 12 are mounted within the annulus between the axial-air pipe 3 and the surrounding outer pipe 8 of the assembly 1.

The downstream ends of pipes 12 are secured to the assembly by means of annular member 13. Annular member 14, which is secured to annular member 13, has a plurality of holes drilled at an angle through said member, one hole for each of the fuel-oil pipes 12. Each hole

tread grades of black; whereas, FIG. 4 is designed for the production of carcass grades.

Referring to FIG. 3, preheated air passes through annulus 23 formed by shell 24 and inner tube 25. Portions 5 of the air enter the interior of the reactor through louvers 26 in combustion-aid device 27. A portion of the combustion air also enters the reactor through annular opening 28. The downstream end of the reactor can be of any suitable design as for example FIG. 1 of U.S. Pat. No. 3,256,065 or FIG. 1 of U.S. Pat. No. 3,256,066.

The preheated combustion air enters the reactor of FIG. 4 as shown. The downstream end of the reactor of FIG. 4 can be of any convenient design, as for example FIG. 1 of U.S. Pat. No. 2,976,127.

We normally atomize the liquid hydrocarbon fuel outside of the reactor, prior to supplying such fuel oil to pipe 11, with any convenient carrying fluid such as steam, air, natural gas, hydrogen or the like. In addition, the fuel droplets, suspended in the carrier fluid, are further atomized at the nozzle.

EXAMPLES

The table below lists typical operating conditions which have been satisfactorily employed for commercial operations while utilizing the burner and feedstock injection assembly of FIGS. 1 and 2. The normally-liquid fuel used was naphtha of a gravity of about 75° API. The feedstock was a highly-aromatic tar from a thermal cracking unit having a gravity of about —1.5° API.

is equipped with a spray nozzle 15 (preferably a flat-spray nozzle) inclined at an angle of about 15°—45° (preferably 15°—25°) from the axis of the center pipe. It would be obvious to those skilled in the art that annular members 13 and 14 could be replaced by an annular member containing an annular groove so that the number of fuel-oil pipes 12 could be less than the number of nozzle 15.

Preferably, the assembly includes a substantially cone-shaped device 16 mounted concentrically about the end of pipe 8, the cone of which flares outwardly toward the interior of the reactor 22 at an angle of about 5°—30° (preferably 10°—15°) from the vertical, said device being comprised of a plurality of vanes or louvers each of which is twisted at the outer end to an angle of about 10°—25°. This device 16 functions as a flameholder or air distribution vane and is advantageous for at least two reasons: (1) it serves to control at least a portion of the combustion air flowing downstream along the outer circumference of pipe 8 by preventing such air from blowing the flame to a position too close to axial pipe 3 and the feedstock spray; (2) the twisted vanes or louvers impart a swirling motion to the air, thus helping to disperse the fuel more evenly about the combustion area.

Desirably, the assembly also includes an air inlet 18 and an annular passageway 19 so that a stream of air can be swept through annulus 20 and annulus 19 and then to the reactor, in order to help cool the spray nozzles 15.

FIGS. 3 and 4 show the preferable positioning of burner and feedstock injection assembly 1 in the upstream end of an elongate tubular carbon black reactor 22. Preferably, the assembly is slideably mounted in the reactor so that the position of the assembly within the reactor can be varied in order to adjust the properties (particularly modulus and structure) of the carbon black.

Although the specific design of the elongate tubular carbon black reactor is not critical to the practice of this invention, we prefer the design shown in FIGS. 3 and 4.

FIG. 3 is particularly suitable for the production of

While we have thus described the preferred embodiments of the present invention, many variations will be suggested to those skilled in the art. The foregoing description and examples should therefore not be considered limitative; and all such variations and modifications as are in accord with the principles described are meant to fall within the scope of the appended claims.

Having thus described our invention, we claim:

1. In combination with an elongate, substantially tubular carbon black reactor, a burner and feedstock injection assembly concentrically disposed within said reactor at the upstream end thereof, said assembly comprising:
  - a center pipe for introduction of feedstock into the reactor, one end of said pipe terminating within the reactor and being equipped with a spray nozzle;
  - a second pipe, concentrically disposed about the center pipe, one end of the second pipe terminating approximately flush with the end of the center pipe within the reactor;
  - a third pipe, concentrically disposed about the second pipe, one end of the third pipe terminating within the reactor at a point upstream of the end of the center pipe;
  - a substantially frusto-conical device mounted concentrically to the outer circumference of the third pipe at the downstream end of said third pipe, said cone flaring outwardly from said third pipe toward the interior of the reactor at an angle of about 5°—30° from the vertical, said device being comprised of a plurality of vanes or louvers each twisted at the outer end thereof to an angle of about 10°—25°;
  - a plurality of fuel-oil pipes disposed within the annulus between the second and third pipes and axially parallel to said pipes, said fuel-oil pipes terminating at a point within the reactor downstream of the end of the third pipe but upstream of the end of the center pipe, the ends of said fuel-oil pipes being connected with a plurality of fuel-spray nozzles each of which

is inclined at an angle of about 15°-45° from the axis of the center pipe;
 means for supplying carbon black feedstock to the center pipe;
 means for supply cooling medium to the annulus between the first and second pipes;
 means for supplying a normally liquid hydrocarbon fuel to the fuel-oil pipes;
 means for introducing a stream of process air into said reactor; and
 means for directing said stream of process air downstream along the outside of the third pipe.

2. The combination of claim 1 in which the fuel spray nozzles are flat spray nozzles.

3. The combination of claim 1 in which there are three fuel-spray nozzles spaced apart at about 120°.

4. The combination of claim 2 in which there are three fuel-spray nozzles spaced apart at about 120°.

5. The combination of claim 4 additionally including means for supplying air to the annulus between the second and third pipes; and an annular passageway, between the outer circumference of the second pipe and the nozzled ends of the fuel-oil pipes, connecting said annulus with the interior portion of the reactor.

6. The combination of claim 1 in which the frustoconical device flares outwardly at an angle of about 10°-25° from the vertical and the spray nozzles are inclined at an angle of about 15°-25°.

5

7. The combination of claim 2 in which the frustoconical device flares outwardly at an angle of about 10°-25° from vertical and the flat-spray nozzles are inclined at an angle of about 15°-25°.

8. The combination of claim 3 in which the frustoconical device flares outwardly at an angle of about 10°-25° from the vertical and the flat-spray nozzles are inclined at an angle of about 15°-25°.

9. The combination of claim 4 in which the frustoconical device flares outwardly at an angle of about 10°-25° from the vertical and the flat-spray nozzles are inclined at angle of about 15°-25°.

10. The combination of claim 5 in which the frustoconical device flares outwardly at an angle of about 10°-25° from the vertical and the flat-spray nozzles are inclined at an angle of about 15°-25°.
